(57) **CLAIM**

The ornamental design for a panel for a container, as shown and described.

DESCRIPTION

FIG. 1 is a top perspective view of a container including the present panel;

FIG. 2 is a front view of the panel of FIG. 1;

FIG. 3 is a left side view of the panel of FIG. 1, the right side view being a mirror image of same; and,

FIG. 4 is a top view of the panel of FIG. 1.

The structure shown in broken lines is for environment purposes only and does not form part of the claimed invention.
